No. 37,173.

Patented October 11, 1904.

UNITED STATES PATENT OFFICE.

ADOLF GENT, OF HOBOKEN, NEW JERSEY, ASSIGNOR TO WILLIAM SCHIMPER & COMPANY, OF HOBOKEN, NEW JERSEY, A FIRM.

DESIGN FOR A TOOTH-BRUSH HOLDER.

SPECIFICATION forming part of Design No. 37,173, dated October 11, 1904.

Application filed August 19, 1904. Serial No. 221,435. Term of patent 7 years.

To all whom it may concern:

Be it known that I, ADOLF GENT, a citizen of the United States, and a resident of Hoboken, in the county of Hudson and State of New Jersey, have invented a new, original, and ornamental Design for a Tooth - Brush Holder, of which the following is a specification.

The accompanying drawing illustrates in front perspective a tooth-brush holder embodying my new, original, and ornamental design.

What I claim is—

The ornamental design for a tooth-brush holder, substantially as herein illustrated.

ADOLF GENT.
